Design No. 18,283, dated May 1, 1888.

UNITED STATES PATENT OFFICE.

OTTO BARTEL, OF NEW YORK, N. Y.

DESIGN FOR A CLOCK-DIAL.

SPECIFICATION forming part of Design No. 18,283, dated May 1, 1888.

Application filed March 21, 1888. Serial No. 266,017. Term of patent 3½ years.

To all whom it may concern:

Be it known that I, OTTO BARTEL, of New York city, New York, have invented and produced a new and original Design for a Clock-Dial, of which the following is a specification.

The accompanying illustration represents a face view of my newly-designed clock-dial.

The leading feature of this design consists of a graduated circle containing the representation of a windmill.

a represents a graduated circle with the numerals from 1 to 12. Within this circle there is contained the representation of a windmill, *b*, having vanes *c*.

The windmill is represented as surrounded by a landscape that is fringed by a mountain range. A farm-house and a cart are also represented.

What I claim is—

The design for a clock-dial, consisting of a circle containing the representation of a landscape, mountain range, farm-house, and windmill, substantially as shown.

OTTO BARTEL.
